UNITED STATES PATENT OFFICE.

ALEXANDER ELI RANDLE, OF GRAYVILLE, ILLINOIS.

DOOR-HANGER.

SPECIFICATION forming part of Letters Patent No. 726,190, dated April 21, 1903.

Application filed May 23, 1902. Serial No. 108,696. (No model.)

To all whom it may concern:

Be it known that I, ALEXANDER ELI RANDLE, a citizen of the United States, residing at Grayville, in the county of White and State 5 of Illinois, have invented a new and useful Door-Hanger, of which the following is a specification.

This invention relates to devices employed for suspending doors or other closures from 10 horizontal tracks; and it has for its object to simplify and improve the mechanism whereby the bearing pulleys or rollers are supported, adjusted, and controlled and also to simplify and improve the suspension-track and 15 its supports.

Other novel features of the invention will appear in the accompanying description and be specified in the claims following.

In the drawings illustrative of the invention, Figure 1 is a side elevation of a pair of doors and a section of the track with the improved hanger applied. Fig. 2 is an enlarged side view of the operative parts detached. Fig. 3 is a vertical section on the line III III 25 of Fig. 2.

This device is applicable to any form of door or other similar closure arranged to move upon overhead horizontal tracks, and for the purpose of illustration it is shown applied to 30 ordinary doors. These hangers are generally applied to double doors, and in the drawings portions of a pair of such doors are shown at 10 10^a. The track is generally in two sections, each section a little longer than twice 35 the width of the door and united centrally with a removable bridge-piece to provide for the removal of the doors without disturbing the tracks, as hereinafter shown.

In the present invention portions of the 40 two sections of the track are shown at 11 11^a and are preferably of steel bars having rounded upper surfaces, as shown in Fig. 3. The tracks are supported at intervals by brackets 12, the brackets being preferably of sheet- 45 steel bent to shape and engaging the track by being passed through apertures therein and riveted on the opposite side, as indicated in Fig. 1. The brackets will be connected by

screws 12^a or other means to the usual framing-timbers or to the studding, joist, or floor-timbers, according to the structure of the building, and I do not wish to be limited to any specific part of the building as a means of supporting the hangers, as they will be attached to whichever part is most convenient. 50

The ends of the track-sections are provided with "gains" or recesses 14, adapted to register with reversely-formed recesses upon a short section of track 15, which forms a "bridging" piece to connect the adjacent 60 ends of the track-sections. These recesses in the ends of the track and bridge sections are formed by forming at each end of said sections two spaced parallel longitudinally-extending arms 14^a and 14^b, one of which is 65 made shorter than the other. The length of the bridging-section will correspond to the width of the hanger-frame, so that the doors may be removed from the track, as herein-after explained. 70

Each end of each track-section will be provided with the recesses 14 to enable the tracks to be changed end for end, so that the track-sections may be employed interchangeably. This is a great convenience and simplifies the manufacture and use of the tracks. 75

The apertures in the adjacent confronting ends of the track-sections 11 and 11^a and the connecting-bridge 15 for the reception of the brackets 12 are continuations of the recesses 80 14, and said brackets will, as shown, not only engage said apertures but project over the horizontal surface of the recess, whereby the same screw which secures the bridge-piece to the track secures the brackets in the apertures. 85

The rollers or pulleys are represented at 16 and are formed with half-round concaved rims to engage the upper surface of the rails, as shown. 90

The hangers for the pulleys are of sheet metal, preferably steel, and will be "struck up" from a single piece, with a front or main portion 17 and rear portion 17^a, bent around from the front portion and parallel thereto, 95 the axle 16^a for the pulley engaging the parts

17 and 17^a by its ends, as shown. By this means the two parts 17 17^a form a firm support to the pulley on both sides. The part 17 extends downward, as at 17^b, and is bent 5 outward and upward, as at 17^c, and thence doubled backward upon itself and carried around in engagement with the extension 17^b at 17^d, and thence outward again beneath the track, as at 17^e, and thence upward parallel 10 to the part 17^b and in front of the track, as shown at 17^f.

Resting upon the outturned portion 17^e is a plate 18, having a depending rib or flange 18^a extending between the portions 17^b and 15 17^d and secured in place by a rivet 19, passing through the three portions, as shown.

The plate 18 extends below the lower line of the track and, in conjunction with the ground 17^a, will prevent the pulley from jumping the 20 track.

The depending "loop" formed by the bend at 17^d provides a hanger for supporting a wedge-bar 20, the bar having a central recess to receive the portion 17^d and prevent longitudinal movement of the bar. 25

The bar 20 is straight on its lower side and inclined on its upper side and disposed above a base-plate 21, attached to the upper edge of the door, as shown.

30 Attached to the door or base-plate 21 on either side of the loop 17^d are keepers 22 22^a, embracing the wedge-bar and forming hangers for the suspension of the base-plate from the wedge-bar and pulley-hanger, as shown.

35 The keepers 22 22^a are preferably formed of steel rods in inverted-U shape, with the legs passing through the base-plate 21 and riveted on the other side. By this arrangement it will be readily understood by adjusting the 40 keepers 22 22^a longitudinally upon the wedge-block the base-plate 21, together with the door connected to it, will be correspondingly adjusted vertically.

The base-plate 21 is turned up at its outer 45 end, as will be seen at 21^a, and this upturned end is provided with a perforation in which is rotatably mounted a screw-bolt 21^b, said screw-bolt being tapped into the smaller end of the wedge-bar, as shown.

50 The screw-bolts are set at an incline, as shown, so that they can be reached by a screw-driver from below the hanger-slot to adjust them without removing the door, and will be swiveled in the projections 21^a, so as to have 55 both a rotary movement and a vertical movement to provide for their proper action at all times upon the wedge-bars no matter what the position of the latter may be. By this means the door may be adjusted longitudinally with reference to the wedge-blocks to

60 any required extent whereby the same will be adjusted vertically. This makes a very simple, cheap, and inexpensive door-hanger of few parts, and therefore not liable to become 65 disarranged. It is very easily applied and

adjusted and will require much less labor and skill to place it in position. It will operate fully as effectually as any of the more expensive and complicated devices employed for the same purpose and with greater simplicity and ease. The pulleys will preferably be provided with ball-bearings to reduce friction. 70

By forming the track semicircular on its traction side and the pulley 16 to correspond 75 the friction is greatly reduced and consequent wear and abrasion correspondingly reduced.

The device can be adapted to any-sized door, gate, or other closure—such as doors 80 in dwellings, or barn or warehouse-doors or sliding gates or other closures—and is admirably adapted to any locality where such sliding closures are employed.

Having thus described my invention, what 85 I claim is—

1. In a door-hanger, a track having recesses in the ends, with apertures extending inwardly from said recesses, brackets formed of sheet metal and engaging said apertures 90 and extending into said recesses, bridging track-section having recesses engaging said track-recesses and the bracket supported therein, and a bolt coupling said track-section, bridging-section and bracket, substantially as described. 95

2. In a door-hanger, a pulley-supporting frame having one side extending downwardly, doubled upon itself and bent to form a door-support, said bent portion being extended 100 laterally and upwardly to form a guard, in combination with a brace supported upon the lateral portion of the frame and bearing against the upwardly-extending guard to brace the latter. 105

3. In a door-hanger, a pulley-supporting frame having one side extending downwardly, doubled upon itself and bent to form a door-support, said bent portion being extended laterally and upwardly to form a guard, in combination with a brace supported upon the lateral portion of the frame and bearing at one end against the upwardly-extending guard and having its opposite end extended upwardly between the side members of the 110 frame and there secured. 115

4. In a door-hanger, a pulley, a supporting track, a hanger-frame for said pulley extended downwardly and formed into a loop, an inclined bar engaged by said loop, a door, keepers engaging said bar on opposite sides of said loop and attached to said door, and means for longitudinally adjusting said inclined bar, substantially as described. 120 125

5. In a door-hanger, a pulley, a supporting track, a hanger-frame for said pulley extended downwardly and formed into a loop, an inclined bar engaged by said loop, a door, a base-plate carried by said door and having 130

an upturned end, keepers attached to said base-plate and engaging said inclined bar on opposite sides of said loop, and an adjusting-screw movably engaging said upturned end, 5 and adapted to adjust said inclined bar longitudinally in said keepers, substantially as described.

In testimony that I claim the foregoing as my own I have hereto affixed my signature in the presence of two witnesses.

ALEXANDER ELI RANDLE.
